UNITED STATES PATENT OFFICE.

BEN McCRARY, OF HOT SPRINGS, ARKANSAS.

STATION-INDICATOR.

SPECIFICATION forming part of Letters Patent No. 274,355, dated March 20, 1883.

Application filed November 15, 1882. (No model.)

To all whom it may concern:

Be it known that I, BEN McCRARY, of Hot Springs, in the county of Garland and State of Arkansas, have invented a new and Improved Street and Station Indicator, of which the following is a full, clear, and exact description.

The object of my invention is to provide a new and improved device for indicating the several streets or stations of a horse-car or stage-line route successively, and to call the attention of the passengers to the indicator every time the same arrives at the name of a street or station.

15 The invention consists in a board containing the name of the streets or stations, over which board a pointer-nut is moved by turning a screw-shaft on which the pointer-nut is mounted, which pointer-nut carries a gong provided with a clapper, which clapper is operated to sound the gong at each station or street name by a stud projecting from the indicator-board opposite the corresponding names of the streets or stations. The screw-shaft can be 20 rotated by hand or automatically from the vehicle axle or wheel.

Reference is to be had to the accompanying drawings, forming part of this specification, in which similar letters of reference indicate corresponding parts in all the figures.

30 Figure 1 is a front elevation of my improved street and station indicator. Fig. 2 is a cross-sectional elevation of the same and of part of the car-floor. Fig. 3 is an enlarged detail view 35 of the pointer and the gong-clapper.

The names of the streets or stations are arranged in their proper order within a frame, B, which is secured in a conspicuous place within the stage or car. The names may be 40 placed on removable slides, or they may be fixed permanently, as the circumstances may require. A vertical screw-shaft, A, is journaled in the frame B, and passes through a nut, C, which is adapted to travel up and 45 down in a vertical groove or slot, D, between the two vertical rows of street or station names.

On the nut C a pointer, E, is formed, which points to the names of the streets and stations.

An arm, F, is pivoted to the other end of the 50 screw-nut C, and its inner end terminates in two curved spring-prongs, G G, provided at the ends with knobs or balls J, which are adapted to strike against a gong or bell, K,

which is held on the nut C and covers the clapper G J. A spiral spring, L, on the pivot 55 of the arm F, always draws the arm F back into the horizontal position.

At the outer end of the arm F jaws M are formed, in which an L-shaped piece, O, is pivoted, the inner arm of the said L-shaped piece 60 resting on a spring, P, held between the jaws M, which spring holds the L-shaped piece O in place. A series of studs, R, project from the surface of the indicator-board at the names of the streets or places. If the nut C is moved 65 up or down, the piece O strikes against the said studs, and thereby the clapper is held for a moment, and is then suddenly released and strikes the gong, thereby calling the attention of the passengers to the indicator. A 70 bevel-cog wheel, a, is mounted on the lower end of the screw-shaft A, and engages with a bevel-cog wheel, b, on a horizontal shaft, S, below the car-bottom.

The shaft S can be provided with devices 75 by means of which the driver or conductor can rotate the same to indicate streets; or the shaft S can be connected with the wheel or axle of the vehicle, so that the apparatus will work automatically.

Parts of the station-indicator can be used for advertising.

Having thus described my invention, what I claim as new, and desire to secure by Letters Patent, is—

1. In a street and station indicator, the combination, with the frame B, containing the names of stations or streets, of the screw-shaft A, the nut C, having a pointer, E, the pivoted arm F, the spring-prongs G, terminating in 90 balls J, the gong K, and the studs R, substantially as herein shown and described, and for the purpose set forth.

2. In a street and station indicator, the combination, with the frame B, containing the 95 names of stations and streets, of the screw-shaft A, the nut C, having a pointer, E, the gong K, the clapper F G J, the L-shaped piece O, the spring P, and the studs R, substantially as herein shown and described, and for the 100 purpose set forth.

BEN McCRARY.
